M. HORNSTEIN

CLOSURE DEVICE

Filed Sept. 26, 1921

UNITED STATES PATENT OFFICE.

MICHAEL HORNSTEIN, OF PATERSON, NEW JERSEY.

CLOSURE DEVICE.

Application filed September 26, 1921. Serial No. 503,193.

To all whom it may concern:

Be it known that I, MICHAEL HORNSTEIN, a citizen of Poland, residing at 44 Clinton Street, Paterson, in the county of Passaic 5 and State of New Jersey, have invented certain new and useful Improvements in Closure Devices, of which the following is a clear and exact specification, reference being had to the accompanying drawings, 10 which form a part of this specification.

This invention relates to doors or swinging closure members, and my improvement is directed to means whereby a device of this character is capable of opening in either 15 direction, it being provided for this purpose with engaging means at each side which serve both as hinges and locks, having the characteristics of both these instrumentalities.

20 For this purpose the pivots of the hinges are retractable whereby the hinge portions that are attached to the closure member become free and thereupon the closure member can be swung open using the opposite 25 hinges as its fulcrum. Since the hinges at the opposite sides of the door or closure member are similarly operable it is immaterial whether the hinge pivots be retracted from the hinges at one side or the other of 30 the door, because when the hinge pivots are removed at one side then the hinges at the opposite side of the door are those upon which the door hangs in its swinging movement, in or out.

35 Means are provided at each side of the door to automatically lock the hinge pivots in their retracted positions while the door is open, these locking means being automatically releasable upon the closing of the 40 door to thus leave the hinge pivot freely operable for engagement when the door is in a closed position.

It is sometimes desirable to remove a door 45 from its hinges, and this can be easily accomplished with my invention, by simply retracting the hinge pivots at one side of the door opening the door at that side and extending the bolts again. Then, upon re- 50 tracting the bolts at the other side the door is freed from its supports, and can be removed.

Other features and advantages of my in- 55 vention will hereinafter appear.

In the drawing:

Figure 1 is an elevation of a door equipped with my combined bolts and hinges.

Fig. 2 is a section on the line 2—2 of Fig. 1, and

Fig. 3 is an enlarged detail of one form of actuating mechanism for the hinge pivots. 60

In carrying out my invention I cause the door or other closure device equipped therewith to be mounted on hinges at both its side ends, but in each instance the hinge pivots are retractable to also serve the purpose of 65 bolts, and each pivot-bolt, or pair thereof, at the respective sides of the door is provided with a separate operating handle.

I have shown in Fig. 1 a door 1, to which are secured the butt hinge portions 3, for 70 alignment with the complementary hinge portions 2 that are secured to a door casing 4. The hinges are shown respectively in upper and lower positions relatively to the door, and are provided respectively with 75 the upper and lower pivots 5, 6, which also constitute bolts, wherefore they are designated herein as pivot-bolts. These pivot-bolts operate in guides 7, and, at their inner ends are in pivotal engagement, respectively, 80 with bars 8, 9, that, at their opposite ends are mounted, by pivots 10, 11, upon a plate 12, which is inserted within and secured to the door.

The bars 8, 9, each carry a pin 13, these 85 pins being entered within oppositely angled, upper and lower slots 14 formed in a plate 15 that is slidable horizontally in guides 16 carried by the fixed plate 12. Since the slots 14 have outwardly converged relation, 90 the effect of sliding the plate 15 inwardly will be to retract the pivot-bolts 5, 6, causing them to disengage the hinge portion 2, leaving the door free to be swung open upon its opposite, similar hinges, and, conversely, the 95 effect of sliding the plate 16 outwardly will be to retract the pivot-bolts, for re-engagement with the hinge portions, when the door is closed, to bolt or latch it.

An operating handle 17 is carried by a 100 post 18 that is mounted on the plate 12, and engages a slot 15^a in plate 15, said post having a lever arm 19, from which a pin 20 projects and engages a slot 21 formed in the plate 15, whereby, upon operating handle 105 17 to turn post 18, the plate 15 is moved in or out according to the direction of handle operation.

A detent bar 22, having an upper slot 23 and a lower slot 24, is mounted thereby upon 110 studs 25, 26 respectively, which are secured to the door, the slots permitting a slight

amount of vertical movement to the bar, which is normally urged upwardly by a spring 27, to bear against the casing upper portion. The bar 22 carries a horizontal stop 5 finger 28, which lies below a finger piece 29 that projects from the slide plate 15, in the outward position of the latter with the pivot-bolts in hinge engagement. But when the slide 15 is drawn inwardly, thereby re- 10 tracting the pivot-bolts, to unlock the door, the finger piece 29 moves out of the vertical path of stop 28, so that, upon opening the door, and the consequent spring extended movement of bar 22, when released from the 15 casing, stop finger 28 is thereby carried into endwise abutting relation with finger piece 29, preventing the extension of the bolts while the door remains open, thus leaving the open door at all times capable of closure. 20 But if the detent bar 22 should be depressed manually, as by pressing downwardly upon its upper end 22^a, then the handle can be turned to extend the bolts.

The pivot-bolts 30, 31 shown in Fig. 1 at 25 the other side of the door, may be provided with identical associated parts and mechanism as have been described in connection with the bolts 2 and 3. Those parts and mechanism which are alike have been 30 given corresponding reference characters. But I have also shown, in connection with the bolts 30, 31 a modified form of control mechanism wherein the bars 8, 9 are connected, by toggle arms 32, 32, with a link 33 35 that is pivoted to the free end of an arm 34 carried by the handle post 18. The pivotal connection 32^a for arms 32 is shown as slide- 40 able in a slot 32^b provided therefor in plate 12. A pawl 35 pivoted at 36 to plate 12, is mounted on the detent bar 22, which engages 45 by a slot 22^b therein with a pin 8^a carried by bar 8, to co-act therewith, the pawl 35 being held upwardly upon said arm 34 when the toggle is expanded to extend the pivot- 50 bolts. But when the toggle is contracted, thereby retracting the bolts, the pawl 35, upon the withdrawal of detent 22 which occurs while the door is opening, is moved into horizontal abutting relation with the 55 arm 34, against the tension of spring 27, and thus holds the pivot-bolts retracted for door closure purposes.

Normally it is desirable that the bolting means at one side only of the door are to be 55 capable of operation, so that if the handle at one side be turned to release its pivot-bolts the other handle will be incapable of similar operation. For this purpose I have shown a horizontal bar 36 extended inwardly from 60 the slide plate 15, and in opposed alignment with bar 36, a bar 37, co-active with the toggle arms 32, is shown as extending rear- 65 wardly from the pivot 32^a, the clearance between the opposed ends of bars 36, 37 being only sufficient to permit the inward move-

ment of one of the bars at a time. Therefore, when one of the handles 18 has been turned to retract its pivot-bolts the bar 36 or 37 will come into abutting relation with the other of said bars, and thereby serve as a 70 stop to prevent the bolt withdrawing operation of the other handle.

It is a purpose with my invention that the door shall open away from the side at which the handle is placed, this being a useful provision for fire and panic doors, and therefore I have mounted the handles respectively at 75 opposite sides of the door, and provided the respective casing engaging means in such manner that the door will open, at each side, 80 away from the person operating the handle.

Variations within the spirit and scope of my invention are equally comprehended by the foregoing disclosure.

I claim:

1. The combination, with a closure device, of hinge parts on opposite sides thereof capable of mating with complementary hinge parts on a casing, removable hinge-bolts to engage the respective hinge parts, bars respectively in pivotal engagement with the inner ends of the pivot bolts, the bars extending inwardly and having fixed pivotal means at their inner ends, a horizontally slidable plate having forwardly converged 90 slots, means respectively carried by said bars to engage said slots, a handle having a shank, and means of engagement between the shank and plate to move the plate in accordance with the direction of rotation of the shank, whereby the bars are swung to or from each other, communicating their movement to the hinge bolts.

2. The combination, with a closure device, having hinge parts on opposite sides thereof capable of mating with complementary hinge parts on a casing, removable pivot-bolts to engage the respective hinge parts, separate means for actuating the pivot-bolts, and handles at opposite sides of the closure device 105 to operate said actuating means for the engagement and disengagement of said pivot-bolts, of normally separated opposed members extended from and operable respectively by the bolt actuating mechanism at 110 each side of the closure member, whereby, when said mechanism at one side has been actuated, the member extended from such mechanism will engage the member extended from the mechanism at the other side of 120 the closure member and thereby prevent its operation.

3. The combination, with a closure device, having hinge parts on opposite sides thereof capable of mating with complementary hinge parts on a casing, removable pivot-bolts to engage the respective hinge parts, separate means for actuating the pivot-bolts, and handles at opposite sides of the closure 125 device to operate said actuating means for 130

the engagement and disengagement of said pivot bolts, of a vertically operating detent carried by the closure device, spring means normally urging said detent against the casing that it may be retracted thereby on closing the door, and means carried by the actuating means for the pivot-bolts to engage the detent when the pivot-bolts are in their

retracted positions to prevent their extension while the door is open, said detent being ¹⁰ subject to manual retraction.

Signed at New York, in the county and State of New York, this 23rd day of September, 1921.

MICHAEL HORNSTEIN.
